UNITED STATES PATENT OFFICE.

LOUIS H. BRADY, OF KANSAS CITY, MISSOURI.

GAS-BURNER.

942,709.

Specification of Letters Patent. Patented Dec. 7, 1909.

Application filed September 24, 1907. Serial No. 394,283.

To all whom it may concern:

Be it known that I, LOUIS H. BRADY, a citizen of the United States, residing at Kansas City, in the county of Jackson and 5 State of Missouri, have invented certain new and useful Improvements in Gas-Burners, of which the following is a specification.

My invention relates to improvements in gas-burners, and pertains more particularly 10 to that type employed in steam-power plants.

One of my objects is to provide a simple burner of few parts any one of which may be easily removed without disturbing the 15 others, so that the cost of repairs or renewal of parts may be reduced to a minimum.

The invention provides for a thorough admixture of gas and air and an equal distribution of heat beneath the boiler, so that 20 the greatest economy and efficiency will be had.

It also provides for rapidly increasing the capacity of the burner above normal so that 25 in case of an emergency the temperature of the boiler may be instantly raised.

Other features of the invention will hereinafter appear, and in order that it may be 30 fully understood, reference will now be made to the accompanying drawings, in which:—

Figure 1 represents a horizontal section, on line I—I of Fig. 3, of a boiler-furnace provided with my improved gas-burners. Fig. 2 represents a vertical section of same 35 on line II—II of Fig. 1. Fig. 3 represents a broken front elevation of the boiler-furnace provided with my improved burners. Fig. 4 is a longitudinal section of one of the burners in an operative position in the front 40 part of the furnace. Figs. 5, 6, and 7 are cross-sections on lines V, VI, and VII, respectively, of Fig. 4.

1 designates a furnace of ordinary construction, provided with the customary 45 bridge-wall 2.

3 designates a boiler of ordinary or preferred form.

4 designates a pair of short burners which 50 only extend through the front wall of the furnace so that the flames therefrom will pass beneath the entire length of the boiler.

5 designates a pair of long burners which 55 extend through the front wall of the furnace and the bridge-wall, so that the flames issuing therefrom will discharge into the com-

bustion-chamber 6. This arrangement of short and long burners insures an equal distribution of heat throughout the furnace and consequently the boiler will be uniformly heated its entire length. All of the 60 burners receive their supply of gas from a header 7, extending across the front of the furnace and communicating with the burners through supply-pipes 8, which are provided with valves 9 for controlling the flow 65 of gas to the burners. By thus supplying the burners separately it is obvious they can be controlled independently of each other. The burners being alike except as to length, I will proceed to describe but one of them 70 in detail, reference being had more particularly to Figs. 4 to 7, inclusive.

10 designates a tubular casing which is firmly set in the front wall of the furnace for the purpose of reliably supporting the 75 movable parts of the burner.

11 designates a mixing-tube which is arranged concentrically within the casing, to leave an annular air-passage 12 between it and said casing. The forward end of tube 80 11 terminates a short distance within the forward end of casing 10 so that the latter will protect the forward end of a sliding-damper, hereinafter described, from the flame. Tube 11 is supported within casing 85 10 by fingers 13 and set-screws 14, which latter are screwed tightly into contact with the tube, to reliably hold it in position while in operation or permit of its removal when it is desired to repair or renew the same. 90

15 designates a mixing-chamber, the forward tapered end of which frictionally engages the rear end of the mixing-tube, so that when necessary it may be removed therefrom. Said mixing-chamber is provided at its enlarged open end with a cap 16 95 which is removed for the admission of air when the burner is in operation.

To provide for a thorough admixture of air and gas, I discharge the latter from a 100 ring 17 located within chamber 15 so that the gas will flow the full length of the mixing-tube with the air and thus have ample time to thoroughly commingle therewith before discharging into the furnace. Ring 17 105 is provided at its rear side with perforations 18 so that the suction created by the air passing through the mixing-chamber 15 and tube 11 will draw the gas from the ring instead of impeding its discharge therefrom, 110

hence there will be no danger of the flame passing backward into the boiler-room.

19 designates a union whereby the ring is connected to its respective supply-pipe 8.

5 The sliding-damper, above referred to, consists of a rod 20, a knob 21 at the rear end thereof, and a disk 22 at the forward end thereof. Disk 22 is perforated to come minute and insure a thorough admixture of 10 the air and gas at its discharge from the forward end of the tube 11. Said damper extends through the mixing-tube and partly through the mixing-chamber, it being slidably and centrally supported within the 15 mixing-tube by a pair of bearings in the form of screw-eyes 23. The sliding movement of the damper is limited by a pair of stops 24 extending through rod 20 and adapted to contact with screw-eyes 23. By 20 arranging knob 21 within the mixing-chamber 15, where it will be exposed to the cold air entering said chamber, it is obvious that said knob will not become too warm to be grasped with the bare hand, and hence the 25 damper may be operated without discomfort to the attendant.

25 designates an annular damper surrounding the rear end of casing 10 and the tapered portion of mixing-chamber 15 30 for the purpose of regulating the flow of air to the air-passage 12, which is accomplished by sliding the damper forward more or less upon the casing to admit the desired quantity of air. This damper, however, is 35 only opened in case of an emergency when it is desirable to rapidly increase the capacity of the burner above normal. It is provided with a pair of handles 26 to facilitate its manipulation.

40 27 designates a perforated-wall within the furnace between the bridge-wall 2 and the inner ends of the short burners, so that the flames discharged therefrom will impinge against said perforated-wall and insure complete combustion of the gas and thorough 45 distribution of the heat.

I provide convenient lighting means for the burner in the form of a small pipe 28, the upper end of which communicates with 50 header 7, while its lower end terminates in a nozzle within the front end of a small tube 29 extending through the front wall of the furnace adjacent to one of the short burners, so that when the valve 30, controlling the flow of gas through pipe 28, is 55 opened, and a lighted match is placed in tube 29 the gas issuing from the nozzle will become ignited and produce a flame which will extend into the furnace through tube 60 29. Hence when the short burner adjacent thereto is turned on the gas therefrom will become ignited and produce a flame, which

in turn will ignite the gas from the other burners when they are turned on.

In operation, cap 16 is removed from the 65 mixing-chamber so that the supply of air through the latter and the mixing tube will be controlled entirely by the sliding-damper which is adjusted to admit the desired quantity of air. Although sufficient air for ordinary purposes may be admitted through the mixing-chamber, in case of an emergency requiring a rapid increase in temperature, valve 9 is opened to its full capacity and the annular damper 25 is also opened to admit 70 an additional supply of air for the additional supply of gas. Then as the rich admixture discharges from the forward end of the mixing-tube it will be spread in funnel-form across the path of the inflowing air 75 entering through passage 12, by means of disk 22, so that the additional supply of air and gas will become thoroughly mixed before ignition takes place.

Having thus described my invention, what 85 I claim is:

1. A gas-burner consisting of a tubular casing, a mixing-tube arranged concentrically therein and of less diameter than the same to leave an annular air-passage between it and the casing, means for controlling the flow of air through said passage, means for discharging gas into the mixing tube, and a sliding-damper extending 90 through said mixing-tube for regulating the 95 flow of air therethrough.

2. A gas-burner consisting of a tubular casing, a mixing-tube removably arranged within the casing and of less diameter than the same to leave an annular air-passage between it and the casing, a damper slidably mounted within the mixing-tube, and an annular damper for controlling the flow of air through the air-passage between the casing and the mixing-tube.

3. A gas-burner consisting of a tubular casing, a mixing-tube arranged therein and of less diameter than the same to leave an annular air space between it and the casing, a mixing-chamber having a tapered end 110 communicating with the mixing-tube, an annular damper slidably embracing the casing and adapted to contact with the tapered portion of the mixing-chamber, means for discharging gas into the mixing-chamber, 115 and a damper in the mixing-tube for controlling the flow of air therethrough.

In testimony whereof I affix my signature, in the presence of two witnesses.

LOUIS H. BRADY.
